UNITED STATES PATENT OFFICE.

C EDWARD LAWSON, OF GARBER, OKLAHOMA.

UNDERREAMER.

Application filed November 19, 1925. Serial No. 70,021.

To all whom it may concern:

Be it known that I, C EDWARD LAWSON, a citizen of the United States, residing at Garber, county of Garfield, and State of 5 Oklahoma, have invented certain new and useful Improvements in Underreamers, of which the following is a specification.

This invention relates to improvements in boring devices and has particular reference 10 to under-reamers used in connection with well casings of oil wells, or the like, for under-reaming the wall of the well to permit the use of additional tube sections or casings.

15 An important object of the invention resides in the provision of a device of the above character so constructed that the mud or drillings cannot interfere with its working parts.

20 Another object is to provide means for maintaining certain cutter elements in retracted or inoperative position during the lowering of the device into the casing.

25 A further object resides in the particular construction and arrangement of the cutters and the means for preventing their removal from certain associated parts.

Still further objects and advantages of the 30 invention will become apparent as the description unfolds, and in order that the same may be better understood reference is had to the accompanying drawing forming a part of this specification.

In said drawings:

35 Figure 1 is a central longitudinal section of the invention, illustrating the same in operative or working position.

40 Fig. 2 is a view like unto Fig. 1, but showing the parts in inoperative position, or more precisely, as the device appears when 45 being lowered into the casing.

Fig. 3 is a transverse section taken on line 3-3 of Fig. 1 to illustrate certain inset blocks carrying pivoted lugs.

45 Fig. 4 is a similar section taken on line 4-4 of Fig. 2 to show certain runners or riders.

Fig. 5 is a transverse sectional view taken on the line 5-5 of Fig. 1; and

50 Fig. 6 is a similar view taken on the plane of the line 6-6 of Fig. 2.

Experience gained by practical men engaged in the operations of well-boring has taught and demonstrated the short-comings and disadvantages of the under-reamers now in use. Some of these comprised a relatively

large number of complicated parts, easy broken or disarranged, with the result that said parts fall to the bottom of the well, which requires the tedious operation of fishing them out or a final abandonment of the well. Still other of the under-reamers have their working parts exposed to the mud and drillings within the well with the result that the satisfactory manipulation of the 60 same is seriously impaired.

Having in mind the defects and disadvantages of the present under-reamers, I have devised an implement simple and inexpensively manufactured, yet admirably 70 performing its duties in a manner as will presently appear.

To this end I have constructed a device comprising upper and lower members 10 and 11 respectively, threadedly connected together as at 12, said upper member being technically termed a "sub" and having a plug 13 at its upper end for connection to a string of tools, (not shown). Said lower member 11, which I term the body portion, 80 is provided with a longitudinal bore 14, extending from the top of the body 11 and terminating intermediate its ends, as clearly shown in Figs. 1 and 2. The lower end of said body portion 11 is reduced to form 85 the squared longitudinally extending head 15, thus defining shoulders 16, the purpose thereof will be pointed out hereafter in the specification.

Slidably connected to said squared head 90 15 is a sleeve or tubular member 17, having diametrically opposed slots 18-18 for the reception of pins or screws 19-19, which latter engage said head 15 and thus permits the reciprocation of said sleeve 17 on said 95 head 15.

A tapered nose or cap 20 closes the bottom of said sleeve 17, and is provided with a central opening 20^a for the reception of the headed rod 21, which extends through said sleeve 17 and the central opening 15^a of said head 15 and into the bore 14 of said body 11. The upper end of said rod 21 carries a piston-like block 22 which is bored out, as indicated at 22^a for the reception of a spring 100 23, the lower end of the latter abutting the shoulder 24 in the bore 14 and being held in tension when in the position indicated in Fig. 2, by means of nuts 25.

The description thus far points out that 110 the sleeve 17 can reciprocate upon the head 15, such reciprocation being limited by the

compressibility of said spring 23 and the screws 19 operating in said slots 18. The slot and screw arrangement has really been introduced as a means of safety, for in the event said rod 21 should part, the sleeve and its associated parts will be held to said head 15 by said screws abutting the top of the slots. This is a feature of some importance, since the danger of parts dropping 10 into the well is positively avoided.

Inset blocks 26-26, carrying pivoted lugs 27-27 are positioned within the opposed openings 28-28 in said body 11, said lugs being operated by runners or riders 29-29 15 as will presently appear.

I now direct particular attention to the cutter elements 30, which are provided with a shank portion 31 pivotally mounted in said cap 20 and normally being held in retracted 20 position by means of leaf springs 32-32. These cutters are each longitudinally grooved to snugly fit about the rod 21 when in retracted position, while the projections 33 lie in the path of the head 15. From the 25 base of said projections the tops of the cutters are inclined downwardly, as indicated at 34, and merge with the cutting edges 35. The base of each cutter is given a double slanted cut to the shank portion 31, the cut 30 36, adjacent the shank portion and the inclined portion 34 and also the projection 33 are adapted to fit within opposed slots 37-37 in said sleeve 17 and the shape of said slots in cross-section is an exact counterpart of 35 these portions of the cutters above referred to. In other words, when the cutters are expanded, as in Fig. 1, they coincide positively with the slots and by reason of this sealing prevent any mud or drillings from 40 entering said sleeve 17. This feature is not found in the present-day under-reamers and those skilled in the art will at once recognize its value.

The foregoing description covers the essential parts of my under-reamer and after 45 due consideration of the operation, about to follow, it is believed the efficiency and reliability of my improved device will become apparent.

50 In operation, the device is lowered into a casing in the position as indicated in Fig. 2. The block 22 is held in position by the lugs 27 engaging the beveled face 22^a by the runners 29, which latter slide down the casing until they reach the bottom thereof, whereupon they fall into the hole, thus 55 releasing the lugs 27 which assume the position indicated in Fig. 1, permitting the spring to expand and carry upwardly all 60 the parts associated with the rod 21. At this point it may be well to note that since said runners 29 are preferably made of cast iron, they are easily ground up in the hole during the drilling. The sleeve 17 now rises 65 bodily upon the head 15, whereupon the first

cam surface 38 of said head 15 engages the projections 33 of said cutters, forces them apart, while the second cam surface 39 completely expands the cutters to the operative position as indicated in Fig. 1. 70

When the reaming has been completed the device is drawn upward out of the hole, whereupon the tops 34 of the cutters come in contact with the bottom edge of the casing, holding sleeve 17 stationary until the 75 body portion 11 is pulled upward and assumes the position indicated in Fig. 2, compressing the spring 23 and finally withdrawing the cutters into the sleeve which permits the device to be removed from the well 80 through the casing. It will be observed that during the lowering and raising operations, the cutters are at all times within the confines of the sleeve 17.

Obviously minor modifications and 85 changes in the device as illustrated may be resorted to liberally which fall within the spirit of the invention or the scope of the appended claims. 90

I claim:

1. An under-reamer comprising a body portion having a longitudinal bore, a tubular member slidably connected to said body portion and having side slots, cutters mounted within said tubular member, said cutters having a configuration conforming to said slots in cross-section, a head operatively mounted within said tubular member and having its lower side portions provided with a double-cam surface, and a spring-pressed rod operating within the bore in said body portion and adapted to force said head into engagement with said cutters for expanding the same. 95

2. An under-reamer comprising a body portion having a longitudinal bore, a tubular member slidably connected to said body portion and having side slots, cutters mounted within said tubular member, a cam-surfaced head operating within said tubular member, a spring-pressed rod operating within the bore in said body portion and adapted to force said head into engagement with said cutters for expanding the same and means associated with said body portion for holding said spring-pressed rod in lowered position. 105

3. An under-reamer comprising a body portion, having a longitudinal bore, a tubular member slidably connected to said body portion and having opposed slots, a head mounted in said tubular member and having a cam surface, cutters mounted within said tubular member, a rod connected to said tubular member and said body portion, a block carried by the upper end of said rod, a spring mounted between said block and the bottom of said longitudinal bore, and means comprising pivoted lugs adapted to hold said body portion and said tubular member in 110 115 120 125 130

spaced relation and also adapted to release said rod to allow said spring to force said head into engagement with said cutters for expanding the same.

4. An under-reamer comprising a body portion having a longitudinal bore, a tubular member slidably connected to said body portion, cutters mounted within said tubular member, a cam-surfaced head operating

within said tubular member, spring-pressed reciprocating means operating within the bore in said body portion and adapted to force said head into engagement with said cutters for expanding the same and means carried by the tubular member for retracting 15 said cutters.

In testimony whereof I affix my signature.
C EDWARD LAWSON.
